UNITED STATES PATENT OFFICE.

HILDA M. LARSON, OF TACOMA, WASHINGTON.

REPRODUCER.

Application filed April 16, 1927. Serial No. 184,368.

This invention aims to provide novel reproducing mechanism adapted to carry the needle which cooperates with a phonograph disk.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed; it being understood that 15 changes in the precise embodiment of the invention herein disclosed, may be made within the scope of what is claimed, without departing from the spirit of the invention.

In the drawings:

20 Figure 1 shows in elevation, a cabinet wherein the device forming the subject matter of this application has been embodied, parts being in section;

25 Figure 2 is a diagrammatic plan showing how the device hereinafter described may be installed;

Figure 3 is a vertical sectional view taken through the cabinet and the horn;

30 Figure 4 is a side elevation showing the device constructed in accordance with the invention;

Figure 5 is an elevation of the structure shown in Figure 4;

Figure 6 is a plan showing a modification;

35 Figure 7 is an elevation of the structure shown in Figure 6.

If desired, the invention may be used 40 with a cabinet 1 wherein a table 2 is journaled, the table being adapted to carry a record disk 3, means 4 being supplied for rotating the table 2. In the cabinet 1 is located a horn 5 or its equivalent, an amplifying means being shown at 6 and being connected by conductors 14 with a battery 7.

45 A reproducer 8 is mounted on the horn 5. A tone arm 9 is mounted at 10 for horizontal swinging movement and has an extension 11 that is pivotally mounted at 12 to swing vertically. The device hereinafter described 50 may be used with such a mechanism as that hereinbefore set forth, but I do not bind myself to use the construction which I have described.

55 In carrying out the invention as shown in Figure 4, there is provided a frame 15, which is a composite structure, including an

angle bracket 16 having a main flange 17 and an auxiliary flange 18 disposed at right angles to the main flange 17. The numeral 19 marks a sleeve, the forward end of which is cut off at a bevel, as shown at 20. In the side of the sleeve 19 there is a set screw 21, and on the lower forward part of the sleeve 19 there is an abutment lug 22. A permanent magnet 23 is disposed against the flange 17 of the angle bracket 16, and the outer surface of the magnet 23 is engaged by a retainer plate 24 through which passes a securing element 25, such as a bolt, the bolt extending backwardly through the flange 17, through the bottom portion of the sleeve 19, and through the abutment lug 22, a nut 26 on the bolt 25 bearing against the lug 22. Coils 27 are mounted on the poles of the magnet 23 and are connected by a conductor 28. The coils 27 are connected at 29 to conductors 30 which extend backwardly through the sleeve 19 and through the tone arm 9 to the amplifying means 6.

A rib 31, in the form of a plate, is secured to the flange 17 of the angle bracket 16 and is provided at its lower end with a bearing 32 in which is pivoted at 33, intermediate its ends, an armature 34 adapted to cooperate with the poles of the magnet 23, the armature being supplied intermediate its ends with a holder 35 operating in an opening 36 in the flange 18 of the angle bracket 16, the holder being adapted to retain a needle 37 which follows the sound groove of the record 3 on the table 2. The movement of the armature 34 is limited by adjustable stops 38, such as screws threaded into the flange 18 of the angle bracket 16.

The groove of the record 3 receives the 95 needle 37, the armature 34 moves with respect to the poles of the magnet 23, and the current flow through the conductor 30 fluctuates in a way well understood by those skilled in the art, the amplifying means 6, 100 the reproducer 8 and the horn 5 exercising their usual functions.

In carrying out the invention as shown in Figure 6 there is provided a frame 15^a which is a composite structure including an angle bracket 16^a having a main flange 17^a and an auxiliary flange 18^a disposed at right angles to the main flange 17^a. The numeral 19^a marks a sleeve, the forward end of which is connected at 39 to an abutment strip 40. In the side of the sleeve 19^a there is a set screw 21^a. A permanent mag-

net 23^a is disposed against the flange 17^a of the angle bracket 16^a, and the outer surface of the magnet 23^a is engaged by a retainer plate 24^a through which passes a securing element 25^a, such as a bolt, the bolt extending backwardly through the flange 17^a and through the abutment strip 40, a nut 26^a on the bolt 25^a bearing against the abutment strip 40. Coils 27^a are mounted on the poles of the magnet 23^a and are connected electrically as hereinbefore described, and as shown in Figure 5. A rib 31^a, in the form of a plate, is secured to the flange 17^a of the angle bracket 16^a, and is provided at its end with a bearing 32^a in which is pivoted at 33^a, intermediate its ends, an armature 34^a adapted to cooperate with the poles of the magnet 23^a, the armature being supplied intermediate its ends with an angular holder 35^a operating in an opening in the flange 18^a of the angle bracket 16^a, the holder being adapted to retain a needle 37^a which follows the sound groove of the record, as hereinbefore described.

25 Generally stated, the form depicted in Figures 7 and 6 does not differ in operation from the form shown in Figures 4 and 5, the armature 34^a being limited in its movement by the adjustable stops 38^a, the sleeve 19^a being held by the set screw 21^a on the pivoted extension 11 of the tone arm 9, and the sleeve 19 being similarly held in place by the set screw 21.

What is claimed is:—

35 1. In a device of the class described, a sleeve provided with an abutment, an angle bracket comprising main and auxiliary flanges, a magnet disposed against the main flange, a retainer cooperating with the magnet, a securing element passing through the retainer, the main flange and the magnet, and engaging the abutment, coils on the

poles of the magnet, an armature pivoted intermediate its ends and cooperating with the poles of the magnet, and means carried by the auxiliary flange for limiting the movement of the armature, the armature being supplied with a needle holder.

2. In a device of the class described, an angle bracket comprising a main flange and an auxiliary flange, a magnet cooperating with the main flange, a retainer engaging the magnet, a securing element engaging the retainer and the main flange to bind the magnet between the retainer and the main flange, coils on the poles of the magnet, an armature, a needle holder carried by the armature, means for mounting the armature pivotally, intermediate its ends, in operative relation to the poles of the magnet, and means carried by the auxiliary flange of the angle bracket for limiting the movement of the armature.

3. In a device of the class described, a supporting member, a magnet disposed against the supporting member, a retainer engaging the magnet, a securing element engaged with the retainer and with the supporting member and binding the magnet thereagainst, coils on the poles of the magnet, a bearing on the supporting member, an armature cooperating with the poles of the magnet and mounted pivotally intermediate its ends on the bearing, the armature being supplied intermediate its ends with a needle holder, and means movable in the supporting member on each side of the needle holder for engaging the ends of the armature to limit the movement thereof.

In testimony that I claim the foregoing as my own I have hereto affixed my signature.

HILDA M. LARSON.
